PEROXYSULFATE-DIETHYLENETRIAMINE
PENTAACETIC ACID COMPOSITION

Gordon I. Jenkins and Elbert V. Kring, Wilmington, Del., assignors to E. I. du Pont de Nemours and Company, Wilmington, Del., a corporation of Delaware
No Drawing. Filed July 1, 1959, Ser. No. 824,175
3 Claims. (Cl. 252—102)

This invention relates to solid bleaching and cleansing compositions containing a peroxyomonosulfate compound which can be effectively employed in practically any common tap water. More particularly, this invention relates to solid bleaching and cleansing compositions containing a novel combination of a peroxyomonosulfate compound and a sequestering agent.

It is well known that peroxyomonosulfate compounds containing HSO_5^- such as NaHSO_5 and KSO_5 are highly effective bleaching compounds, being stronger oxidizing agents than hydrogen peroxide and many other commonly used per compounds. However, the use of such strong oxidizing agents in common tap water presents a problem because some tap water supplies contain manganese in amounts of about 0.1 p.p.m. or more. Analysis has shown that ordinary tap water rarely contains more than 0.2 p.p.m. manganese. Under the influence of peroxyomonosulfates the manganese becomes oxidized to a high valence state (+3 or +4) and imparts a yellow discoloration to the object being treated. The problem especially acute when white cloth is laundered or white porcelain is cleansed. Tests have shown that as little as 0.1 p.p.m. manganese in the water will noticeably discolor white cloth or porcelain when manganese is oxidized to a higher valence state.

It has been found that manganese ions can be effectively sequestered from the oxidizing action of peroxyomonosulfate with diethylenetriamine pentaacetic acid (DTPA) or the alkali metal salts thereof and that these sequestering agents are not attacked by peroxyomonosulfate to an appreciable extent. It has also been found that DTPA does not decompose peroxyomonosulfate to any appreciable extent. Additionally, it has been determined that the monopersulfate compound and DTPA may be formulated in solid bleaching and cleansing compositions which can be added to common tap water containing substantial amounts of manganese with the result that the latter is effectively sequestered so that it will not discolor the substrate being bleached.

It is an object of the present invention to provide solid bleaching and cleansing compositions containing peroxyomonosulfate that can be effectively used in virtually all tap water.

It is another object of the present invention to provide solid bleaching and cleansing compositions that contain a sequestering agent for manganese, which agent is not antagonistic to the bleaching agent.

It is still another object of the present invention to provide solid bleaching and cleansing compositions that contain a sequestering agent that will rapidly form a complex ion with manganese.

The occurrence of substantial amounts of manganese in water supplies is not unusual; common tap water will occasionally contain more than 0.1 p.p.m. manganese.

2

Normally, the presence of manganese is not detrimental in bleaching solutions, since conventional bleaching agents do not oxidize manganese to a yellow-colored oxidation state.

5 In the table below, the various concentrations of Mn^{++} were obtained by adding increasing amounts of manganese sulfate to distilled water and the bleaching composition below was added to each solution. The term "Oxone" refers to a mixture of KHSO_5 , KHSO_4 and K_2SO_4 in mole proportions of 2/1/1, and KHSO_5 , the active oxygen source, constitutes about 50% by weight of the mixture.

	Percent
"Oxone" -----	35
Sodium sulfate -----	20
Sodium metasilicate -----	5
Sodium carbonate -----	20
Tetrasodium pyrophosphate -----	20

10 Each solution contained about 0.2% of the composition together with an equal amount of detergent; and standardized washing machine conditions were employed, peroxyomonosulfate supplying 25 p.p.m. active oxygen. White cotton cloth swatches at a cloth/water ratio of 1/20 were used in the bath at 140° F. and the time of wash cycle was 10 minutes.

Manganese Concentrations (p.p.m.)	Reflectance as a Function of Wash				
	0	1	2	3	4
	0.00	86.8	87.3	87.0	87.7
0.05	86.1	87.1	87.1	87.0	86.4
0.10	86.7	87.1	85.8	83.5	80.6
0.20	86.4	86.8	84.7	80.8	76.6
0.30	86.9	86.8	83.4	79.6	75.2
0.50	87.0	86.0	82.1	77.2	73.7

40 The cloth was given a thorough rinse after washing and then dried. After the wash and dry cycle, the reflectances of the swatches were determined in a Hunter multipurpose reflectometer using a blue filter, the fall in reflectance representing a measure of the yellowing of the fabric. The results show that even small concentrations (about 0.1 p.p.m.) of manganese are oxidized and cause yellowing.

45 50 Example 1
The same bleaching formulation containing DTPA, a white powder commercially available as "Perma-Kleer" 140, Refined Products Corporation, was employed under the same conditions as noted above in an amount equal to about 6% by weight based on potassium peroxyomonosulfate content and the DTPA was mixed in the formulation prior to use. The water was common tap water containing about 0.2 p.p.m. manganese. The discoloration that resulted from yellowing under identical conditions when DTPA was not added is also shown. It is to be noted that the use of DTPA caused no significant decomposition of the peroxyomonosulfate ions as indicated by active oxygen analysis.

Composition of Table I	Residual Active Oxygen, p.p.m.	Reflectance as Function of Wash					
		0	1	2	3	4	5
With DTPA	16	84.0	85.8	85.6	85.4	85.4	85.5
With no DTPA	17	85.6	84.9	83.0	80.0	76.5	73.8

Example 2

This example illustrates the effect of DTPA when used in a cleanser. A use-worn sink was scoured with the following cleanser:

	Percent
"Oxone"	2.5
Sodium carbonate	2.5
Soap	6.0
Abrasive powder (silica or feldspar)	89.0

The cleaning was carried out using tap water containing approximately 0.3 p.p.m. manganese and the cleaned portion of the sink was allowed to stand in water for 15 minutes between each cleaning treatment. After 8 washes a distinct yellow discoloration was apparent. On a separate section of the same sink the above formulation containing 6% DTPA (based on the weight of potassium peroxyomonosulfate, the preferred source of active oxygen) was used. After 8 washes there was no visible discoloration.

In addition to diethylenetriamine pentaacetic acid, the alkali metal salts of the acid are equivalents and are also excellent sequestrants for manganese. Thus, sodium or potassium may be substituted in any or all of the five carboxyl groups of DTPA as noted in Example 3. The structures of DTPA and DTPA-5 Na are as follows:

Example 3

DTPA-5 Na is commercially available as the 40% active water solution and is known as "Versenex" 80 (Dow Chemical Company). Solid DTPA-5 Na can be readily obtained by conventional drying methods. Using the same formulation under similar conditions as noted in Example 1 in tap water containing about 0.2-0.3 p.p.m. manganese, the following results were obtained when 40% active solution of DTPA-5 Na was added simultaneously with the addition of the bleach formulation. The amount of 40% solution of DTPA-5 Na added constituted about 20% based on the weight of potassium peroxyomonosulfate.

Composition of Table I	Reflectance as Function of Wash							
	0	1	2	3	4	5	6	7 . . . 14
With DTPA-5 Na	86.0	87.4	87.5	86.8	87.0	87.2	87.1	87.0
With no DTPA-5 Na	86.5	85.9	84.9	82.4	80.5	78.2	-----	-----

Example 4

Peroxyomonosulfate can be used with a source of chloride ions as a heavy-duty bleach and as an effective

bleach for nylon and other synthetics. A typical heavy-duty bleach includes:

	Percent
"Oxone"	20
Sodium chloride	60
Potassium carbonate	15
Tetrasodium pyrophosphate	5

The same washing conditions employed in the previous examples prevailed in an experiment using tap water containing about 0.2 p.p.m. manganese and about 0.3% of the heavy-duty bleach. About 20% by weight (of 40% active solution DTPA-5 Na) based on potassium peroxyomonosulfate content was added at the same time the bleaching composition was added to solution. Cotton swatches were repeatedly bleached with this solution and an identical solution containing no sequestrant with the following results:

Heavy-Duty Bleaching Solution	Reflectance as Function of Wash							
	0	1	2	3	4	5	6	7
With DTPA-5 Na	86.5	86.9	86.5	85.7	85.4	84.1	83.0	82.0
With no DTPA-5 Na	86.5	85.9	84.9	82.4	80.5	78.2	-----	-----

Peroxyomonosulfate compounds in combination with DTPA or its equivalents can be used in a variety of bleaching, laundering and cleansing formulations. The compositions specifically set forth above are representative and should not be construed to be limiting. Ordinarily, these formulations are used in alkaline solutions. However, peroxyomonosulfates in combination with DTPA can be used in either acid or alkaline solutions. Moreover, this combination can be used as a bleaching composition alone. Normally, the amount of active oxygen supplied by the peroxyomonosulfate will vary from about 5 to 600 p.p.m. Throughout the specification, percentages and parts are calculated on a weight basis unless otherwise designated.

It has been found that solid bleaching compositions and cleansers that contain an alkali metal peroxyomonosulfate and DTPA and its equivalents may be added to practically any tap water without discoloring the object being treated. The amount of DTPA and its equivalents must be at least 0.01 part by weight based on each part of alkali metal peroxyomonosulfate content; preferred compositions contain 0.02-0.1 part of the former to each part of the latter, although there is no critical upper limit to the amount of the sequestrant used.

The solid compositions of the present invention are stable under normal storage conditions. Contributing to the uniqueness of compositions containing the two ingredients is the fact that upon the addition of water, neither ingredient is antagonistic to the other, and the sequestrant operates rapidly to prevent the peroxyomonosulfate from oxidizing manganese. These conditions prevail throughout the relatively short time required for bleaching and cleansing.

Other common sequestering agents were not effective because they either did not prevent yellowing or reacted with the bleaching agent. Reaction with the bleaching agent would impair the bleaching effectiveness of the bleaching and cleansing compositions and is therefore unacceptable.

To be effective, it is essential that the sequestrant have all of the desirable characteristics in solution for at least a relatively short period of time under household conditions. The outstanding sequestrant for this use is diethylenetriamine pentaacetic acid and alkali metal salts thereof. Other agents which theoretically should sequester manganese have been found to be much less effective.

The embodiments of the invention in which an exclusive property or privilege is claimed are defined as follows:

1. A composition consisting essentially of an alkali metal peroxyomonosulfate and a compound selected from the group consisting of diethylenetriamine pentaacetic acid and alkali metal salts thereof, at least 0.01 part by weight of said last named compound being present for each part by weight of said peroxyomonosulfate.

2. A composition consisting essentially of potassium peroxyomonosulfate and diethylenetriamine pentaacetic acid, at least 0.01 part by weight of said acid being present for each part by weight of said peroxyomonosulfate.

3. A composition consisting essentially of 1 part by weight of potassium peroxyomonosulfate and 0.02 to 0.1 part by weight of diethylenetriamine pentaacetic acid.
